UNITED STATES PATENT OFFICE

HERMAN L. HARTBURG, OF DENVER, COLORADO

ELEVATOR

Application filed April 16, 1928. Serial No. 270,490.

My invention relates to elevating means and particularly to means adapted to receive material from a wagon, truck or other receptacle at a lower level and elevate same to a higher level, as into a railway car or into a pile.

An object of the invention is to provide a novel elevating means of the character mentioned for receiving sugar beets dumped from a wagon or truck into the elevator and for transferring the beets to a railway car or beet pile. The invention is, however, not limited to sugar beets, but may as well be used to elevate grain, coal, sand, gravel, etc. Sugar beets will be taken merely as an example in the present specification.

Another object of the invention is to provide a portable elevator of the character mentioned.

A further object is to provide means which in the elevating step provides compartments or bins for the separation of the beets into small groups to facilitate their elevation.

A still further object is to separate dirt, leaves, stems and other foreign matter from the beets before they are dumped into the railway car or pile.

Another object is to provide means for the return of the foreign matter to the wagon originally carrying the beets so that it may be weighed and deducted from the gross weight of the beets in the wagon.

Other objects reside in novel construction and in novel arrangements of parts, too numerous to mention, but which will fully appear in the course of the following description.

In the drawings, in which like reference characters designate like parts in the several views,

Figure 1 is a side elevation, partly broken, of an elevator embodying the features of the present invention.

Figure 2 is a partly broken, side elevation similar to that shown in Figure 1, but looking in the opposite direction.

Figure 3 is a partly broken end view.

Figure 4 is a plan view of the elevator shown in the aforementioned views.

Figure 5 is an enlarged section taken on the line 5—5 of Figure 1.

Figure 6 is an enlarged section taken on the line 6—6 of Figure 1.

Figure 7 is an enlarged section taken on the line 7—7 of Figure 1.

Figure 8 is an enlarged, broken elevation of a corner of the elevating mechanism.

Figure 9 is an enlarged section of an idler for the elevator.

Figure 10 is an enlarged, broken elevation of the driving means for the elevator.

Figure 11 is an enlarged section taken on the line 11—11 of Figure 8.

Figure 12 is an enlarged section taken on the line 12—12 of Figure 11.

Figure 13 is an enlarged section taken on the line 13—13 of Figure 8.

Figure 14 is a broken sectional view of modified mechanism for the elevator.

Figure 15 is an elevation of another such modification.

Figure 16 is a section taken on the line 16—16 of Figure 14.

Figure 17 is a section taken on the line 17—17 of Figure 14.

Figure 18 is a broken elevation of another modified embodiment of the present invention.

Figure 19 is an enlarged view of a chain and belt, forming part of the elevating mechanism of Figure 18.

Figure 20 is an enlarged section taken on the line 20—20 of Figure 18.

Figure 21 is an enlarged section taken on the line 21—21 of Figure 18.

Figure 22 is a broken elevation of a modified elevating mechanism also embodying the present invention.

Figure 23 is an enlarged section taken on the line 23—23 of Figure 22.

Referring more specifically to the drawings, the reference numeral 5 designates the supporting frame for the present elevating mechanism. The frame is supported on a tractor unit 6 and a pivoted wheel 7 at opposite ends.

The frame includes a superstructure 8 for the support of the various elements of the present elevator. The superstructure is partially supported on the frame 5 and partially on a wheel 9, which steadies the elevator. It

may thus be seen that the elevator has a three-point support, to wit, the tractor, the pivoted wheel and the steadyng wheel.

The tractor not only provides motive power for transporting the entire elevator from place to place, but also drives the elevator through the medium of a belt 10 driven by a pulley 12 on the tractor.

A steering wheel 13, provided on the tractor, is connected to rotate the pivoted wheel 7 through the medium of a belt 14. The details of the steering mechanism and of the tractor will not be minutely described since per se they form no part of the present invention.

Supported on the frame, is a feed hopper 15 having converging side members 16 that are strengthened by channel members 17 fastened thereto. Above the converging side members are wall members 18 and 19. The wall member 18, on the side of the hopper from which the beets are dumped into same, is hinged to the adjacent side member as at 20. The opposite wall member 19 is fixed 25 in an upright position.

End members 21 of the hopper have openings 22 for beets on a traveling conveyor 23 hereinafter more fully described.

A plate 24 fastened below the hopper and 30 to the strengthening members 17 provides a track for the conveyor 23, as best shown in Figure 7.

The conveyor consists of parallel chains 25. Square shafts 26 are disposed between 35 the chains for the support of flights 27. The shafts are rounded at the ends for connection with the chains.

Fastened on the shafts between the flights and the chains are cross cam arms 28 having 40 rollers 29 at the extremities of the arms. The rollers travel along the track 24 below the hopper when the conveyor is traveling in a horizontal direction.

Runways 30 are provided for the control 45 of the rollers when the conveyor is traveling from the horizontal position to the top point of its travel. The runways for the rollers are so disposed as to maintain the flights at right angles to the direction of travel during the 50 elevating step.

The chains pass around sprocket wheels 32 and 33 at the top and at one of the lower corners of the elevator respectively. Shaft 34 of the top roller carries a pulley 35 driven by a belt 36, which is mediatly driven by the belt 10 of the tractor unit through a series of belts and pulleys. At the lower side opposite the sprocket wheel 33 the chains are held in position by the runways 30.

The rising stretch of the elevator has stationary walls 31 on three sides to keep beets from falling from the flights. The fourth side of the compartments between the flights 60 is closed by a traveling endless belt 37 on

pulleys 38 and 39. The belt travels at least as fast as the flights.

The upper pulley 39 is driven by a belt 40 that in turn is driven by a pulley 41 on the shaft 34.

Idlers 42 behind the belt 37 maintain same in position against the flights.

Adjacent the top of the elevator, the beets on the flights are dumped into a hopper 43 that feeds onto a screening device 44 having 75 grizzly rollers 45. The rollers 45, which are corrugated and circumferentially grooved to jostle dirt and foreign matter from the beets and move the beets forward to a discharge chute 46, are driven by suitable means indicated generally by the number 47. Scraper bars 48 located on the under side of the screening device are disposed to remove mud and other matter from the grooves of the rollers.

The screening device also has larger circumferentially-serrated rollers 49 driven by rollers 50. The rollers 49 rotate between the smaller rollers 45. These larger rollers remove the loose matter, such as leaves, stems and the like, from the beets on the screen.

The dirt, leaves, stems and all other foreign matter falls or is carried through the screen into a hopper 51 having a gate 52 at a bottom opening thereof. This foreign matter is returned to a truck or wagon 53 below the hopper by opening the gate. In practice it is returned to the wagon or truck that dumped the beets into the elevator.

A tare house 54 is provided adjacent the screen 44 and chute 46, so that a tareman can take a sample of clean beets from the chute 46 for each wagon load of beets.

The chute 46 discharges the beets onto a shuttle conveyor 55 of conventional design, 105 pivoted to the superstructure so that it may be raised and lowered at its outer end for the discharge of beets at any desired elevation. The shuttle conveyor may be operated by any suitable means. The adjusting means for the shuttle conveyor consists of a cable 56 that is fastened to a yoke 57 at the outer end of the conveyor, that is passed around a sheave 58, and wound on a drum 59.

The runways 30 may end at the top roller, 115 thus releasing the cam arms, 28, and allowing the flights to assume a position practically parallel with the chains, as shown in broken lines in Figure 1. The flights remain in the latter position on the descent and while passing through the lower portion of the feed hopper 15.

The various belt-and-pulley and gear connections of the apparatus have not been minutely described, but only suggested, as there is nothing unique about them.

A platform 60 having a railing 61 is provided along the side of the apparatus for the tareman.

In the modified form shown in Figures 14

to 17, flights 62 are pivoted at an edge and not in the longitudinal axis as in the form hereinbefore described.

Each flight has a shaft 63 carrying crank arms 64. One end of the crank arms is fastened to the shaft and the other bears a roller 65. The flights are connected to chains 66 as before.

At the rising corner of the elevator are disposed eccentric sprocket wheels 67 and 68 that are fastened together by links 69. The sprockets 68 are mounted on a shaft 68a, and the sprockets 67 are mounted to revolve freely on bosses 67a, which are secured to the frame by bolts 67b and through which the shaft 68a passes. Each link 69 has one end pivoted to a sprocket 67 and its other end pivoted to the companion sprocket 68. The sprockets 68 are driven by the chain 66 and the sprockets 67 mesh with the crank arm rollers, best shown in Figure 17. By this means the flights are held in a substantially horizontal position while the chains are rounding said corner, and traveling up the ascending stretch.

An endless belt 70, traveling on pulleys 71 and 72 and held against the edges of the flights by idlers 73, is provided as before.

Figure 15 merely shows another method of linking the eccentric sprockets together.

Figures 18 to 21 show an elevator that is square in elevation instead of triangular as hereinbefore.

The elevator means comprises parallel chains 74 as before having tubular shafts 75 between the chains. Flights consist of a plate 76 pivoted at one edge on one of the tubular shafts 75 and at the other edge having brackets 77 carrying rollers 78.

An elastic belt 79, bolted to the tubular shafts as shown at 80, is woven above and below the shafts, as shown in Figure 19. Tracks 81 for the chains are provided in angle members 82 on the frame.

The belt 79 closes one side of the compartments between the flights on the rising side, eliminating a stationary side for the compartments.

The chains travel around large sprockets 83 at the corners of the elevator. On the same shafts and rotatable therewith are smaller sprockets 84, which drive chains 85 carrying lugs 86. Idlers 87 hold the stretch of the chains adjacent the belt parallel to same. An adjustable roller 88 is provided to take up slack in each chain.

Plates 89 are provided at the sides of the compartments on the ascending side to confine the beets between the flights. The lower ends of the plates extend around the corner of the elevator and are pointed as at 90. This pointed end 90 provides an incline to raise the rollers 78, as shown in Figure 18.

The chains 85 are disposed in the path of the rollers, so that the lugs 86 will engage the

rollers 78 and aid in supporting the flights during their ascent, also shown in Figure 18.

The flights divide the beets on the belt into groups for their easy elevation.

The rollers 78 are ahead of the pivoted edges with regard to the direction of travel, while the flights are on the lower horizontal stretch of the elevator. After the flights pass an angle bar 91 on the upper horizontal stretch, they are allowed to hang from the belt, and on the descending side (not shown) of the elevator, the flights are allowed to fall and lie against the belt, so that on the lower horizontal stretch the rollers will be in advance as explained.

A screening device 92 shown in Figure 18 consists of oscillating fingers 93 that advance the beets along the device and separate foreign matter therefrom. Square shafts 94, provided for the fingers, are oscillated by any suitable means.

The elevator shown in Figures 22 and 23 operates on a different principle. The elevator is triangular in elevation, as before, and enclosed in a housing 95. At each corner of the housing is a set of sprocket wheels 96. The sprocket wheels may be operated by any suitable power means.

Endless parallel chains 97 are arranged to travel around the sprocket wheels. An endless belt 98 of flexible material is fastened between the chains 97 by brackets 99.

On the ascending side of the belt is disposed an endless carrier 100 having flights 101 at right angles to the carrier.

Shaft 102 of the sprocket wheels at the lower corner on the ascending side carries a roller 103 for the carrier. A roller 104 is provided near the top of the elevator also for the carrier. The latter roller is driven from the uppermost sprocket wheels by a chain 105.

A receiving hopper 106 is disposed along the horizontal stretch of the elevator for the reception of beets and for their guidance to the belt 98. A receiver 107 is provided adjacent the upper end of the carrier to receive the elevated beets.

In Figures 22 and 23 the belt must travel rapidly enough for the beets to be held against the belt at the ascending corner by centrifugal force. If the belt travels about 600 feet per minute this will be accomplished and the beets will be dropped onto the flights from the belt from above.

In the operation of the present apparatus, the beets are generally brought to the elevator by the wagon or motor truck 53, preferably of a type that can be dumped.

A block and tackle, indicated generally by the reference character 108, suspended from the superstructure may be used to tilt the body 109 of the wagon or truck and dump the beets into the receiving hopper 15. A mechanically driven drum 110 is provided to wind up the tackle to dump the body 109.

In Figure 3 the truck body is shown as having a let-down side 112 for directing the beets to the hopper, the hinged wall member 18 having been previously turned down.

5 The beets are then elevated by any of the several means herein described, to the chute 43, which directs the beets onto the screening device, 44, which separates foreign matter from the beets.

10 The serrated and grooved rollers 45 of the screen jostle the beets together and loosen the dirt therefrom. The dirt drops between the rollers into the dirt receiver 51. As described, leaves, stems, and other bulky foreign

15 matter is carried through the rollers by the large toothed wheels into the dirt receiver.

All dirt and other foreign matter is returned to the farmer by opening the gate 52 and discharging it into the wagon body 109

20 that carried the beets to the elevator.

The wagon filled with beets was first weighed and thereafter the wagon carrying the foreign matter is weighed and deducted from the gross weight, to give the net weight

225 of the beets.

From the screening device 44, the beets are fed down the chute 46 to the shuttle conveyor 55 which feeds the beets into a railway car 113 shown in Figure 3, or into a desired

380 pile.

A tareman takes a sample of each load of beets by taking clean beets passing down the chute 46. The walk 60 is provided for the convenience of the tareman in getting this

385 sample.

The tare house 54 has a bench 114 for testing.

For traveling, the cable 56 is wound onto the drum 59 to fold the conveyor 55 against

40 the superstructure.

By means of the tractor unit 6 the apparatus may be transported from place to place. Thus, piles of beets may be established in different beet raising localities, or the beets

45 may be loaded into a railway car that may be switched onto a siding in a beet raising locality.

Instead of being compelled to construct an elevator in every desired locality, companies

50 making sugar from sugar beets may use one

or more of the present devices and move them

wherever desired.

Having thus fully described my invention, what I claim as new and desire to secure by

55 Letters Patent of the United States is:—

1. An apparatus for the purpose set forth including an elevator consisting of endless chains, independently rotatable rods extending between and pivoted to the chains, cranks

60 on the ends of the rods, flights on the rods, and propelling means including eccentrically connected sprockets engaging said cranks to project the flights into load-sustaining position.

65 2. In an elevator, endless elevating means

having a substantially horizontal stretch and a rising stretch, independently movable flights on said means, the flights being in a substantially horizontal position in the horizontal stretch, means to hold the flights in a substantially horizontal position in going from the one stretch to the other, and means to hold the flights in a substantially horizontal position on the rising stretch.

3. An elevator including an endless chain having a horizontal run and an ascending run, a sprocket wheel engaging the chain, independently movable pivoted flights on the chain, a second sprocket wheel eccentric to the first sprocket wheel and adapted to hold the flights in load-sustaining positions when passing from one run to the other, and means connecting the sprocket wheels whereby they operate synchronously.

4. An elevator including an endless chain having a horizontal run and an ascending run, a sprocket wheel engaging the chain, independently movable pivoted flights on the chain, a second sprocket wheel eccentric to the first sprocket wheel and adapted to hold the flights in load-sustaining positions when passing from one run to the other, and links connecting the sprocket wheels whereby one drives the other.

5. An elevator comprising an endless chain having a substantially horizontal load-receiving run and an ascending run, a sprocket wheel at the junction between said runs, independently movable flights on the chain, and cranks on the flights cooperating with the teeth of the sprocket wheel to maintain the flights in a load-sustaining position until they enter the ascending flight.

6. An elevator comprising an endless chain having a substantially horizontal load-receiving run and an ascending run, independently movable flights on the chain, cranks on the flights, means at a juncture of the runs cooperating with the cranks for maintaining the flights in a load-sustaining position until the latter reach the ascending run, and means for maintaining the flights in a load-sustaining position, during their movement along the ascending run.

7. An elevator comprising endless chains having horizontal and ascending runs, a sprocket wheel at a juncture of the runs engaging one of the chains, a second sprocket wheel eccentric to the first, links operatively connecting the sprocket wheels, independently movable pivoted flights on the chains, and cranks on the flights cooperating with the teeth of the second sprocket wheel to maintain the flights in a load-sustaining position in traveling from one run to the other.

8. An elevator comprising an endless chain having a substantially horizontal load-receiving run and an ascending run, movable flights on the chain, cranks on the flights, means at a juncture of the runs cooperating with the

cranks for maintaining the flights in a load-sustaining position until the latter reach the ascending run, and means cooperating with the flights for maintaining the flights in load-sustaining positions during at least a portion of their movement along the ascending run.

9. In an elevator, a housing and endless elevating mechanism in the housing, comprising an endless chain having a substantially horizontal stretch, a rising stretch and a descending stretch, the housing being open along the rising stretch on the side facing the horizontal stretch, and pivoted flights on the chain, the flights projecting from the chain away from the adjacent portion of the housing, on going from the horizontal stretch to the rising stretch.

10. In an elevator, endless elevating mechanism comprising an endless chain having a substantially horizontal stretch, a rising stretch and a descending stretch and pivoted flights on the chain, a housing for the mechanism disposed to prevent beets from falling off the flights on three sides, the housing being open along the rising stretch on the side facing the horizontal stretch as the flights go from the horizontal stretch to the rising stretch, and a hopper disposed to feed beets to the horizontal stretch and to receive beets dropping through the open side of the housing along the rising stretch.

11. An elevator comprising endless chains having horizontal and ascending runs arranged at an acute angle to each other, a sprocket wheel at the juncture of the runs and engaging one of the chains, a sprocket wheel eccentric to the first sprocket wheel, links operatively connecting the sprocket wheels whereby movement of the chain engaged wheel causes rotation of the second sprocket wheel, flights divided at spaced intervals on the chains for independent swinging movement, cranks on the flights cooperating with the teeth of the second sprocket wheel upon passage of the flights from the horizontal to ascending run, and a support parallel to said ascending run and extending upwardly from the sprocket wheels for at least a portion of said run, said support being positioned to engage and hold the flights passing therewith against downward tilting movement.

12. An elevator comprising endless chains having horizontal and ascending runs arranged at an acute angle to each other, a sprocket wheel at the juncture of the runs and engaging one of the chains, a sprocket wheel eccentric to the first sprocket wheel, links operatively connecting the sprocket wheels whereby movement of the chain engaged wheel causes rotation of the second sprocket wheel, flights divided at spaced intervals on the chains for independent swinging movement, cranks on the flights cooperating with

the teeth of the second sprocket wheel upon passage of the flights from the horizontal to ascending run, and a belt arranged parallel to said ascending run and supported on spaced freely rotatable pulleys, the side of the belt next the ascending run being positioned to engage the free ends of flights passing upwardly along the ascending run and to support said flights against downward tilting movement while in engagement with said belt.

In testimony whereof I have affixed my signature.
